HIS ATTORNEY.

UNITED STATES PATENT OFFICE.

LEWIS C. BAYLES, OF EASTON, PENNSYLVANIA, ASSIGNOR TO INGERSOLL-RAND COMPANY, OF JERSEY CITY, NEW JERSEY, A CORPORATION OF NEW JERSEY.

SHELL FOR ROCK DRILLS.

Application filed February 3, 1927. Serial No. 165,595.

This invention relates to cradles or shells of the type used for supporting and guiding rock drills with respect to the work. More particularly, the invention relates to the feed screw which is operatively connected to the rock drill and the shell for actuating the rock drill longitudinally of the shell, both to advance the drill toward the work in accordance with the penetration of the 10 drill steel into the work and to withdraw the drill steel from the drill hole.

In apparatus of this type it is customary to use a feed screw of considerably greater length than the shell body. This is done 15 to obtain the required travel of the rock drill and at the same time to hold the weight of the shell to a minimum. In consequence of this construction, a considerable portion of the feed screw overhangs the shell body 20 at one end. In order to support this overhanging end of the feed screw, a cross head is provided to rotatably receive the feed screw and the cross head is secured to the shell body by means of side rods or bolts.

Usually, the bolts are passed through two or more ribs on the sides of the shell and spacers in the form of sleeves are placed on the bolts to abut with one end the cross head and with the other end the shell body. 30 In this way the cross head and the spacers are clamped in operative position. While this construction will have the effect of clamping the overhanging elements to the shell body, it does not, however, prevent an 35 objectionable whipping or vibratory movement of the overhanging elements due to the vibration of the rock drill, particularly when the drill occupies a position near the opposite end of the shell.

The present invention aims to eliminate this whipping action of the overhanging portion of the feed screw and also to prevent any distortion of the shell body due to the clamping effect of the side bolts or rods.

Other objects will be in part obvious and in part pointed out hereinafter.

The invention consists of the combination of elements and arrangement of parts having the general mode of operation substantially as hereinafter described and claimed

and illustrated in the accompanying drawings, in which

Figure 1 is a longitudinal side view of a rock drill shell having the invention applied thereto.

Figure 2 is an enlarged view partly in section taken through Figure 1 on the line 2-2 looking in the direction of the arrows,

Figure 3 is an elevation partly in section taken through Figure 2 on the line 3-3 looking in the direction of the arrows, and

Figure 4 is a view similar to Figure 3 illustrating a modification of the invention.

Referring to the drawings, A designates a shell body having an intermediate conical bearing portion B whereby said shell body may be anchored to a column or other suitable device (not shown) for supporting the shell with respect to the work. The shell A is provided with the usual guideways C to receive slidably guides D carried by the cylinder E of the rock drill F. The rock drill illustrated is of the drifter type and supports at its front end, a drill steel G against which the blows of the hammer piston (not shown) may be delivered.

In common with drills of this type, the cylinder E carries near its rearward end a lug H which extends into the shell A and is bored to receive a feed nut J which may be 80 fixedly secured in the lug H in any suitable manner.

The feed nut J is interiorly threaded to cooperate with a feed screw K for actuating the rock drill F longitudinally of the shell A, that is, to advance the rock drill as the drill steel G penetrates the work and also to withdraw the rock drill together with the drill steel from the work after the hole has been drilled.

The feed screw K is preferably anchored rotatably at its front end in a bearing L secured to the front end of the shell A by means of bolts O. In the present instance the feed screw K is of such length that a 95 considerable portion thereof extends beyond the rearward end of the shell A, thus enabling the rock drill F to be retracted a sufficient distance to permit withdrawal of the drill steel G out of the drill hole.

In order to form a support for the overhanging portion of the feed screw K a cross head P is disposed on the rearward end thereof to receive rotatably the feed screw 5 K and also acts as an abutment for a lateral flange Q on the feed screw for preventing relative longitudinal movement between the feed screw and the cross head in one direction. To prevent such movement between 10 the feed screw and the cross head in the opposite direction, a crank handle R disposed on the end of the feed screw bears against the rearward end of the cross head P. The crank handle R may be of any suitable type 15 and in the present instance is clamped on the feed screw K by means of a bolt S. This crank handle R affords a convenient means for rotating the feed screw K to actuate the rock drill F in the shell A.

According to the present invention the shell A is provided at its rearward end and on opposite sides thereof with lugs T and U. The lugs T are preferably formed at the immediate end of the shell and the lugs 25 U or innermost lugs are preferably spaced a slight distance therefrom and in alignment with the lugs T. The lugs T are provided with apertures V to receive sleeves W which extend therethrough and into recesses X in 30 the lugs U. The recesses X are preferably shallow and the bottoms thereof form an abutment for one end of the sleeves W. Apertures Y form a continuation of the recesses X to enable bolts Z to extend therethrough, said bolts extending beyond the lugs U to receive nuts b which bear against 35 the ends of the lugs U.

The opposite ends of the bolts Z are in this instance also threaded and project 40 through lugs e of the cross head P for supporting said cross head, nuts b being provided for clamping the cross head securely in position.

The sleeves W are of such length as to abut 45 with their rearward ends the forward or inner face of the cross head P so that when the nuts b are screwed on the bolts Z the cross head P and the sleeves W will be drawn firmly into operative position.

The sleeves W are preferably so bored 50 that they will fit snugly the bolts Z, thus having the effect of imparting rigidity to said bolts and consequently preventing excessive vibration of the feed screw K. In 55 the present instance the sleeves W also fit snugly the apertures V and the recesses X in the lugs T and U respectively so that when the sleeves W are pressed or driven into the lugs, the sleeves will be slightly contracted to produce a clamping effect at these points on the bolts Z. In this way is formed 60 a rigid construction whereby the objects of the invention are attained.

Besides eliminating vibration of the feed

screw, the present invention also prevents distortion of the shell body. This is due to the fact that both the spacers and the clamping nuts act only on a single lug on each side of the shell, as a result of this, any distortion which may occur will take place only in the 65 lug to which the bolts and spacers are anchored and not in the shell body as has previously been the case where the spacers were abutted against the end of the shell and the nuts acted against a rib or lug spaced from 70 the end of the shell.

In the modification illustrated in Figure 4 lugs d are formed only at the rearward end of the shell A and on the opposite sides thereof. These lugs d are provided with 80 tapered apertures e to receive a tapered end f of sleeves g. The sleeves g may be relieved intermediate their ends as at h so that the said sleeves contact only with the bolts Z at their front end. By thus tapering the 85 ends of the sleeves g, as well as the apertures e, the sleeves g may be firmly drawn into the lugs d by the nuts b without the aid of special appliances for this purpose, and any wear which may occur between the cooperating 90 surfaces of the sleeves g and the lugs d may be readily compensated for by merely tightening up the nuts b. This construction also enables the feed screw supporting elements to be readily disassembled for the 95 purpose of inspection or replacement.

It will be observed that in this modification the sleeves g and the nuts b also both act against the same lugs so that any distortion which may take place will be only 100 in the lugs and will not affect the body portion of the shell. This is an advantageous feature in shells of this type, since it prevents any binding effect of the shell on the guides of the cylinder and therefore protects these parts against wear due to such binding.

It is to be understood that the present showing and description discloses only a few specified modifications of my invention and 110 that the invention is capable of further modification without departing from the spirit thereof or the scope of the claims.

I claim:

1. A shell for guiding a rock drill, comprising a shell body, hollow lugs on opposite sides of the shell body, bolts in the lugs extending rearwardly of the shell body, a cross head supported by the bolts, sleeves on the bolts holding the cross head in spaced 115 relation with respect to the shell body, said sleeves extending into the lugs, and nuts on the bolts bearing against the same lugs into which the sleeves extend to prevent distortion of the shell body.

2. A shell for guiding a rock drill, comprising a shell body, a pair of lugs on each side of the shell body spaced with respect 120

to each other and having apertures there-through, bolts extending through the lugs, a cross head on the outer ends of the bolts, a feed screw supported at one end by the 5 cross head, sleeves on the bolts extending through the outermost lugs and seated with their inner ends in the innermost lugs, and

nuts on the bolts holding the parts securely in operative position, said nuts also seating against the innermost lugs to prevent 10 distortion of the shell body.

In testimony whereof I have signed this specification.

LEWIS C. BAYLES.
